UNITED STATES PATENT OFFICE

SAMUEL JOHANSEN, OF DETROIT, MICHIGAN, ASSIGNOR TO ISABELLA SCOTT AND DAVID J. SCOTT, EXECUTORS OF THE ESTATE OF WALTER SCOTT, DECEASED, OF PLAINFIELD, NEW JERSEY, DOING BUSINESS AS WALTER SCOTT & COMPANY

PAPER HANDLING DEVICE

Application filed January 17, 1930. Serial No. 421,554.

This invention relates generally to machines for handling paper or the like, and has more particularly reference to cylinders used in connection with folding and cutting devices associated with web printing machines.

In the accompanying drawings, the invention is disclosed in several concrete and preferred forms in which

10 Fig. 1 is a general view in elevation and with parts broken away and in section of a folding device embodying the invention;

Fig. 2 is an enlarged sectional view of the folding and cutting cylinders shown in 15 Fig. 1;

Fig. 3 is a fragmentary view looking at a portion of the cylinder face;

Fig. 4 is a view similar to Fig. 2 but showing a modified form of the invention; and

20 Figs. 5 and 6 are detail views showing the adjusting means used in the modified form Fig. 4.

In printing or other machines for handling web material, the web or webs, that is a single 25 layer of paper or a plurality of superposed layers, are supplied at a certain speed. The folding and cutting cylinders at the end of the machine are geared to advance the web at a very slightly greater speed than that of 30 the advance of the paper through the printing machine so as to keep the paper under tension. When different runs are made, different numbers of layers of web material will reach the folding and cutting cylinders, and

35 sometimes the increase in thickness of the paper becomes excessive, especially when successive batches of sheets are cut from the web and collected. The folding or cutting cylinder is provided with web-taking devices such

40 as impaling pins, and it will be understood that, when the thickness of the web layers becomes excessive, the effect is virtually that of a cylinder of increased diameter. The result is that the topmost layers of the pack or batch

45 move at a greater speed than the under layers so that overpulling of some of the webs takes place, usually resulting in disengagement of the webs with the web-taking devices. This is caused by the fact that, as previously stated, 50 the printing cylinders rotate at a given speed

and the web or webs are therefore supplied to the folding cylinders at a given speed, and, as it is difficult, and would be objectionable, for the folder to pull the web over the printing cylinder at a greater speed than the speed of rotation of the printing cylinders, it naturally follows that the paper is torn from the web-taking devices. There are other factors that enter into this. For instance when new blankets are placed on the impression cylinders, the cylinder may have a larger diameter than when the blankets become old and compressed. These variations are, of course, slight, and a certain amount of tolerance is provided for, but there are occasions, nevertheless, when these variations exceed the tolerances allowed and then there may be difficulties.

It is the main object and feature of this invention to provide a construction that will 70 overcome these difficulties.

In Fig. 1 is depicted a folder of a well-known construction to which the invention may be applied. As there shown, 1 indicates a former folder with which is associated the usual folding rollers 2 and 3 by means of which a longitudinal fold is given to the web or webs 4. 5 is a collecting and folding cylinder and 6 is a cutting cylinder cooperating therewith. The web or webs are led between cylinders 5 and 6 where successive cuts are made to produce packs of sheets, and where, at times, successive packs of sheets are collected in a manner well understood, after which the sheets are folded between rolls 7 and delivered by S-delivery 8 or otherwise. Cylinder 5 is here provided with three web-taking devices, taking the form of impaling pins 9, and these pins are mounted on supports 10 of which there are likewise three. Cylinder 6 is provided with two cutting blades 11 that engage rubber members 12 on cylinder 5. Supports 10 are of segmental-shape and are spaced apart as shown, and spanning the gap between said supports are bands 13 of flexible material, such as sheet steel. 14 indicates folding blades to fold the batch of sheets between rolls 7, and these folding blades are geared to so rotate that at the proper moment they will project between the

steel bands and present the sheets to said rolls 7. The details necessary to accomplish this result need not be described as they are well understood in the art.

Now, it will be observed, that at a certain point in the revolution of cylinder 5 the impaling pins engage the layer or layers of web material and that, after the transverse severing of said webs takes place, said impaling pins will continue to advance the severed sheets, and that another set of impaling pins have meanwhile engaged the web or webs to advance the latter. It will now be understood that if an excessive thickness of paper is engaged by the web-taking device the effect is virtually that of increasing the diameter of cylinder 5 so far as the outer layers of paper are concerned. The result is that said outer layers are moving in a longer path, with respect to paper supply means indicated at 3, than do the layers nearer the surface of the cylinder or, to put the matter differently, the outer layers move at a greater speed than the inner ones. There is, therefore, a tendency to overpull the web with respect to 3 and the devices back of it. Again, to illustrate, we may say that the sheet carrying surface of the cylinder, so far as the outer layers are concerned, has been lengthened. This, as previously described, tends to tear the outer layers from the impaling pins. To overcome this difficulty resort is had to the simple expedient of so flexing bands 13 that the paper path is shortened, or the sheet carrying surface is shortened, said bands being brought below the normal circumference of cylinder 5. In this manner the excessive thickness of paper is compensated for and overpulling is avoided. This is illustrated in Fig. 2 where 15 indicates in dotted lines the normal circumference of the cylinder and where bands 13 are shown flexed below said normal circumference. The means for effecting this flexing may, of course, vary widely. In Figs. 2 and 3 the bands are shown as being anchored by means of bolts or set-screws 16 to one of the supports 10, said bands having at their other ends slots 17 in which are fitted dove-tail clamps 18 held by set-screws 19 on another one of the supports 10. Or the set-screws themselves may constitute the clamps. Mounted in said other support 10 is a threaded stem 20 carrying an internally threaded nut 21 which extends up into an opening 22 in a band, and this nut may be provided with wrench holes as 23. It will now be seen that, set-screws 19 being loosened, rotation of nut 21 will adjust the band circumferentially in one direction or the other thereby flexing it more or less. To facilitate this action, the ends 24 of supports 10 may be of slight taper formation. After the proper adjustment has been made, set-screws 19 are brought home to clamp the parts in position. If desired a

gage may be associated with nut 21 to indicate the amount of adjustment required for different thicknesses or layers of paper.

In Figs. 4, 5 and 6 is shown a modified form of the invention. In this case, cylinder 25 is provided with two sets of impaling pins 26 and two rubbers 27. Cylinder 28, on the other hand, carries both a set of impaling pins 29 and a cutting member 30. In this case, therefore, 28 acts not only as a cutting cylinder but also as a collecting cylinder. The invention is here shown applied to cylinder 28. As here shown, cylinder 28 has two supports 31 and 32, the former of which supports the cutting member and also has anchored thereto two sets of bands 33 by means of set-screws 34, and the latter of which carries a rotatable member 35 having two pins 36 one of which engages a transverse slot 37 in one band and the other of which engages a transverse slot 37 in the other band. Said bands are also provided with longitudinal slots 38 in which fit dove-tail clamps 39 held in position by set-screws 40. It will now be understood that, set-screws 40 being loosened, rotation of member 35 will simultaneously flex two bands of different sets. Any suitable means may be used to rotate member 35. For instance, a rotatable worm 41 may be used to engage a worm wheel 42 in member 35. 43 is a pin engaging a circumferential groove 44 in worm 41 to keep the latter from moving lengthwise.

I claim:

1. The combination of a rotating cylinder, means to supply, to the surface of said cylinder, one or more layers of paper webs at a given speed, web-taking devices carried by the cylinder to advance said layer or layers of paper webs under tension by rotation of the cylinder, and means to prevent overpulling of said web layer or layers by said web-taking devices.

2. The combination of a rotating cylinder, means to supply, to the surface of said cylinder, one or more layers of paper webs at a given speed, web-taking devices carried by the cylinder to advance said layer or layers of paper webs under tension by rotation of the cylinder, and means carried by the cylinder to prevent overpulling of said web layer or layers by said web-taking devices.

3. The combination of a rotating cylinder, means to supply, to the surface of said cylinder, one or more layers of paper webs at a given speed, web-taking devices carried by the cylinder to advance said layer or layers of paper webs under tension by rotation of the cylinder, and means to adjust the circumferential length of the surface of the cylinder to prevent overpulling of said web layer or layers by said web-taking devices.

4. The combination of a rotating cylinder, means to supply, to the surface of said cyl-

inder, one or more layers of paper webs at a given speed, web-taking devices carried by the cylinder to advance said layer or layers of paper webs under tension by rotation of the cylinder, and means to vary the length of the paper path between the web supply means and the web-taking devices carried by the cylinder.

5. The combination of a rotating cylinder, 10 means to supply, to the surface of said cylinder, one or more layers of paper webs at a given speed, web-taking devices carried by the cylinder to advance said layer or layers of paper webs under tension by rotation of the cylinder, and means to adjust the circumferential length of the surface of the cylinder to thereby vary the length of the paper path between the web supply means and the web-taking devices carried by the cylinder.

6. The combination of a rotating cylinder, means to supply, to the surface of said cylinder, one or more layers of paper webs at a given speed, web-taking devices carried by the cylinder to advance said layer or layers of paper webs under tension by rotation of the cylinder, and means to adjust the circumferential length of the surface of the cylinder to thereby compensate for a variation in the 30 number of layers of webs on said cylinder.

7. The combination of a rotating cylinder, means to supply, to the surface of said cylinder, one or more layers of paper webs at a given speed, web-taking devices carried by the cylinder to advance said layer or layers of paper webs under tension by rotation of the cylinder, and means to flex the surface of the cylinder to prevent overpulling of said web layer or layers by said web-taking devices.

8. The combination of a rotating cylinder, means to supply, to the surface of said cylinder, one or more layers of paper webs at a given speed, web-taking devices carried by the cylinder to advance said layer or layers of paper webs under tension by rotation of the cylinder, and means to flex the surface of the cylinder to thereby vary the length of the paper path between the web supply means and the web-taking devices carried by the cylinder.

9. The combination of a rotating cylinder, means to supply, to the surface of said cylinder, one or more layers of paper webs at a given speed, web-taking devices carried by the cylinder to advance said layer or layers of paper webs under tension by rotation of the cylinder, and means to flex the surface of the cylinder to thereby compensate for a variation in the number of layers of webs on said cylinder.

10. In a rotating cylinder that carries one or more layers of paper on its surface, supporting members spaced apart circumferentially, flexible bands, constituting a paper

supporting surface, extending circumferentially over the gap between, and carried by, said supporting members, and means to circumferentially adjust said bands to thereby flex them so as to vary the length of the paper 70 supporting surface.

11. In a rotating cylinder that carries one or more layers of paper on its surface, segmental-shape supporting members spaced apart circumferentially, paper-taking devices carried by one of said supporting members, flexible bands, constituting a paper supporting surface, extending circumferentially over the gap between, and carried by, said supporting members, and means to circumferentially adjust said bands to thereby 80 flex them so as to vary the length of the paper supporting surface.

12. In a rotating cylinder that carries one or more layers of paper on its surface, a plurality of supporting members spaced apart circumferentially, a plurality of sets of flexible bands, constituting paper supporting surfaces, extending circumferentially over the gaps between, and carried by, said supporting members, and means to circumferentially and simultaneously adjust members of two sets of bands to thereby flex them so as to vary the length of a plurality of paper 90 supporting surfaces.

13. In a rotary folding machine, the combination with means to supply one or more layers of webs at a given speed, of a combined cutting and folding cylinder to receive said layers on its surface, web taking devices on 100 said cylinder to advance said layer or layers under tension by rotation of the cylinder and, after the web or webs has been severed, to carry around cut sheets to be associated with other sheets or web sections received by the cylinder, and means to vary the effective size of said cylinder to thereby provide for collecting varying thicknesses of product without overpulling.

14. In a rotary folding machine, the combination with means to supply one or more layers of webs at a given speed, of a collecting cylinder to receive said layers on its surface, impaling pins on said cylinder to engage the web or webs, and means to adjust the 110 peripheral length of said cylinder to avoid pulling the impaling pins out of the product that is being collected.

15. In a folding machine, the combination with means to supply one or more layers of webs at a given speed, of a cylinder, devices on the cylinder to take a varying thickness of product, and means to vary the effective size of said cylinder to compensate for the varying amount of thickness of the product. 120 125

Signed at Detroit, in the county of Wayne, and State of Michigan, this 13th day of January, 1930.

SAMUEL JOHANSEN.
